UNITED STATES PATENT OFFICE.

CHARLES WALTER MACWILLIAMS, OF GENEVA, NEBRASKA.

CHIMNEY-COWL.

1,256,917.

Specification of Letters Patent. Patented Feb. 19, 1918.

Application filed April 4, 1917. Serial No. 159,666.

To all whom it may concern:

Be it known that I, CHARLES WALTER MACWILLIAMS, a citizen of the United States, and a resident of Geneva, in the 5 county of Fillmore and State of Nebraska, have invented a new and useful Improvement in Chimney-Cowls, of which the following is a specification.

My invention is an improvement in chimney cowls, and has for its object to provide means in connection with pivotally mounted cowls adapted to be swung by the wind to discharge the smoke in the same direction toward which the wind is blowing for automatically controlling the draft through the 10 cowl in accordance with the speed of the wind, wherein a damper is provided normally counterbalanced to stand in open position, and having a vane connected therewith 15 and mounted to be engaged by the wind to partially close the damper when the wind blows to lessen the amount of draft.

In the drawings:—

Figure 1 is a vertical section through the 20 chimney extension and the cowl, and

Fig. 2 is a section on the line 2—2 of Fig. 1.

The present embodiment of the invention is shown in connection with a chimney 1 of ordinary construction, the said chimney having a metal extension 2, whose upper part is cylindrical, and the said extension has an external rib 3 near its upper end. The cowl consists of an elbow consisting of arms 30 4 and 5, and the arm 4 fits over the upper end of the extension, and engages the rib. The lower end of the cowl is reinforced as indicated at 6 by bending the said end back upon the body and it is this end that 35 engages the rib.

The cowl is pivotally mounted by means of a journal rod 7, which passes at its upper end through a bearing 8 at the axis of the arm 4 of the cowl, and through spiders 9 40 and 10 mounted in the arm 4 and in the cylindrical portion of the extension respectively.

A nut 11 is threaded on to the upper end of the rod and the nut is locked by a cotter 50 pin as shown. Other nuts 12 are threaded on to the rod above and below the bearing of the spider 10 to prevent upward movement of the rod with respect to the exten-

sion. The rod has thus three points of support, namely, the bearing 8 and the spiders 55 9 and 10, and the cowl swings on this pivotal mounting and on the rib 3.

The cowl has the usual vane 13 for constraining the cowl to follow the direction of the wind. The vane is so arranged that 60 the opening or outlet of the cowl will be in the direction toward which the wind is blowing, and the mechanism for controlling the draft through the cowl is controlled directly by the force of the wind. The lower 65 part of the outlet of the cowl is flattened as shown at 14 in Fig. 2, and a damper 15 is mounted at this point.

The damper is provided with a sleeve bearing 16 which is engaged by a pintle or 70 shaft 17, journaled in bearings 18 in the walls of the outlet and having stop collars 19, for limiting the longitudinal movement of the shaft. The shaft or pintle is rigid with the damper, and at one end the 75 shaft has a depending arm 20, which is provided at its lower end with a weight 21.

A vane 22 of approximately triangular shape is mounted on the arm above the weight, the vane having a central bearing 80 23 for receiving the arm. The vane, the weight, and the arm are just enough heavier than the valve or damper 15 to normally hold the same in the full line position of Fig. 1. 85

The vane is however far enough lateral with respect to the cowl that it will receive practically the full force of the wind when it is blowing, and since the vane 13 will always cause the cowl to take a position in line with the direction of the wind and with the outlet away from the wind, the wind will always act upon the vane in a direction to cause it to close or partially close the damper. Thus when the cowl is in the position of Fig. 1 with the wind blowing the valve 15 will be closed to an extent determined by the speed of the wind. The extent of opening through the cowl and as a consequence the draft through the cowl will 90 100 be directly controlled by the force of the wind.

I claim:—

In combination with a chimney, of a cowl journaled on the chimney to swing with 105 the wind on a vertical axis and having a

horizontal discharge portion, and means for constraining the cowl to swing with its discharge end away from the wind, a damper hinged within the horizontal discharge portion to swing into a vertical position across the outlet or into horizontal position resting on the bottom of the horizontal por-

tion, a vane connected with the damper outside of the cowl for engagement by the wind to move the damper into closed or partially closed condition in accordance with the force of the wind, said vane being weighted to normally hold the damper open.

CHARLES WALTER MACWILLIAMS.
